APPARATUS FOR DESTROYING ACID FLAME
IN INTERNAL COMBUSTION MOTOR
GASESArthur W. Reed, Boston, Mass., assignor to Atlas
Power Corporation, a corporation of Delaware

Application January 25, 1938, Serial No. 186,768

2 Claims. (Cl. 123—198)

This invention relates to apparatus for destroying acid flame in exhaust gasses of internal combustion engines.

Attempts have heretofore been made to utilize the exhaust gasses of internal combustion motors for the operation of accessories of which the brakes of a motor vehicle is one good example. However, the presence of acid flame in internal combustion motor exhaust gasses, sets up a high degree of oxidation of metal piping and lines and as previously constructed, in many instances the devices were of faulty operation because of breakage of the pipe lines of the apparatus due primarily to oxidation of the pipe lines which so weakened them that they could not withstand the vibrations to which they were subjected in use.

It is one object of the present invention to provide an apparatus by which the exhaust gasses of internal combustion motors may be treated to destroy the acid flame therein, thereby to reduce or entirely remove the oxidizing action of said gasses at least to the extent where rubber hose may be employed between the apparatus and the accessories operated by the exhaust gasses after they have been treated.

An important feature of the invention resides in a novel construction whereby the apparatus employed for treatment of the exhaust gasses is mounted directly upon an internal combustion motor in such a manner as to vibrate in unison or uniformly with the motor thereby relieving the several connections between the different elements, of all strain incident to or resulting from the operation of the motor.

Another important object of the invention resides in a novel construction whereby proper and efficient operation of an internal combustion motor to which the invention is attached, is in no way affected but operates in a thoroughly normal manner.

With the above and other objects in view, reference will now be had to the following specification and claims and to the accompanying drawing, wherein,

The figure is a fragmentary view of an internal combustion motor, the view being partly in elevation and partly in section.

In the drawing, the reference character A designates the cylinder block of an internal combustion motor, the cylinder head being designated by the reference character B. C designates the compression and firing chamber of one of the cylinders of the motor and it is to be noted that the head B is water jacketed in

accordance with the best construction in internal combustion motors. The reference numeral D designates the circulating medium for effecting continuous flow of a cooling medium throughout the water jacket of the head and block, this portion of the system being shown conventionally herein since its specific construction and design are immaterial to the operation of the apparatus of the present invention, so long as it is capable of maintaining a circulation of cooling fluid to satisfy the demand.

The apparatus of the present invention includes a coil 10 formed from a tube 12 having an extremely small passage 11 therethrough. The coil has one end designated 13, extended through a suitable gland 14 in the outer wall of the water jacket of the head and the extremity of said end is rigidly secured as at 15, to the inner wall of the water jacket of the head. By this construction, the coil is rigidly attached to the internal combustion motor in such a manner that it vibrates in unison therewith in a manner and for a purpose which will be hereinafter described.

The opposite end of the coil 10 is extended as indicated at 16 and secured to the extended end 16, there is a suitable gas take-off device 18.

Surrounding the gas take-off device 18, there is a housing 17, which completely encloses the coil 10. This housing 17, is rigidly connected as at 19 to the end 13 of the coil and as at 20, to the end 16 of the coil and in this manner, the housing is rigidly supported by the coil and vibrates in unison with the coil and motor.

The housing 17, is connected with the circulating system D, by means of a flexible tubing 21, which in turn is connected to a T-coupling 22, connected to the system D by a flexible tubing 23. The housing 17, is also connected to the water jacket of the head B, by a flexible tubing 24.

By the above described construction it will be obvious that when the motor is in operation, cooling fluid will be continuously circulated through the housing 17 and into direct heat transfer relation with the coil 10. As will hereinafter appear, this is an important feature of the present invention.

The reference character 25, designates an expansion tank or chamber which is water jacketed as designated by the reference character 26 and which has a removable top 27 and a drain plug 28. The expansion chamber 25, is rigidly supported upon the head B of the motor by two brackets 29 and by means of a flexible coupling 30, the water jacket of the expansion tank 25,

has communication with the water jacket of the head B. A flexible tubing 31, also connects the water jacket 26 of the expansion tank 25 with the T-coupling 22 heretofore mentioned and through which the water jacket 26 of the expansion tank 25 has direct communication with the circulating system D, of the motor so that when the motor is in operation, a constant circulation of cooling fluid will be maintained through the water jacket 26 of the expansion tank 25.

This expansion tank 25 is connected with the take-off device 18 by means of a suitable pipe line 35, connected as at 36 to the take-off device and as at 37 to the expansion tank 25. The pipeline 35 discharges directly into a coil 38 which in turn discharges directly into the expansion tank 25. Mounted within the tank 25, there is a second coil 40, and having direct communication with this coil 40, there is a flexible line 41, which leads from the expansion tank 25 to the accessory to be operated or to a suitable storage tank, neither of which are herein illustrated.

In operation, when the compressed charge in the compression chamber C is fired, the gasses pass through the very small passage 11 of the coil 10 and in so doing, a high degree of friction is produced by reason of the restricted area of said passage. This high degree of friction created by the forcing through the passage 11, of hot gasses under high pressure, suppresses the flames present in said gasses, completely destroying said flames and appreciably decreasing the temperature of the gasses as they pass through the small orifice of the tube coil 10. Also lending materially to the destruction of acid flame and the reduction of temperature of the gasses as they pass through the coil 10, is the circulation of the cooling fluid through the housing 17 in direct contact with the outer surface of the coil 10.

From the coil 10, the gasses pass through the gas take-off device 18, through the pipe 35 to the coil 38 in the expansion tank 25, from which coil, the gasses are discharged directly into the storage tank.

By reason of the restricted area of the passage 11, through the tube of the coil 10, by the time the gasses reach the gas take-off device, all acid flame therein has been eliminated and they enter the take-off device 18 merely as gasses under pressure containing a certain proportion of condensate or liquid.

As the gasses enter the expansion tank 25, the condensate settles to the bottom of said tank from whence it may be drawn from time to time as occasion may require, merely by removal of the drain plug 28.

The gasses, as they are desired for use may be drawn directly from the expansion tank 25 by means of the coil 40 and the flexible tubing 41, or they may be led from the expansion tank to a suitable storage tank not shown.

From the foregoing, it will be apparent that since all the elements entering into the take-off and expansion of the gasses, are rigidly supported directly by the internal combustion motor and therefore vibrate in unison therewith, thereby relieving all pipe lines and their connections of all strain which results in operation without interruption from broken lines.

Furthermore, the present construction permits of flexible tubing being used between the ex-

pansion tank 25 and the accessory operated by the gasses or the tank in which these gasses are to be stored, and since these elements are generally mounted upon the chassis or body of a motor vehicle, this flexible connection permits of independent vibration of the motor and chassis without resulting in rupture of the lead line as is bound to result in such constructions as require a rigid lead line between the several elements of the apparatus.

While the restricted area of the passage 11 through the tube of the coil 10 has been described as a means for smothering or otherwise destroying acid flame in the gasses of combustion, this passage has another important function which will now be described.

The high resistance to the passage of gasses through the passage 11, maintains a high degree of compression in the compression chamber C, thus insuring firing of the charge and preventing so-called "skipping," of the motor which would inevitably result from a too low compression of the gasses in the compression and firing chamber C.

It will thus be apparent that the present invention provides an apparatus which is highly efficient for the purpose intended and while the invention has been herein disclosed in its preferred form, it is to be understood that it is not to be limited to the specific constructions herein shown and that it may be carried out in other forms within departing from the spirit or scope of the appended claims.

Having thus described the invention, what is claimed as new, is:

1. In combination, an internal combustion motor having a water jacket, a housing supported directly upon said motor, means for circulating the water of the water jacket through said housing, a coil mounted within said housing and having its ends extending through opposite side walls thereof, one of the ends of the coil extending through the water jacket of the motor into communication with the interior of one of the cylinders thereof, a gas take-off device carried by the opposite end of the coil, a gas storage tank mounted directly upon the motor, said gas storage tank having a water jacket therearound, and means for leading products of combustion from the gas take-off device to the gas storage chamber.

2. In combination, an internal combustion motor having a water jacket, a housing supported directly upon said motor, means for circulating the water of the water jacket through said housing, a coil mounted within said housing and having its ends extending through opposite side walls thereof, one of the ends of the coil extending through the water jacket of the motor into communication with the interior of one of the cylinders thereof, a gas take-off device carried by the opposite end of the coil, a gas storage tank mounted directly upon the motor, a water jacket surrounding the gas storage tank and having communication with the water jacket of the motor, means for circulating the water of the motor water jacket through the water jacket of the storage tank, and a pipe connected to the take-off device for leading the gases therefrom to the storage tank.

ARTHUR W. REED.
